CLAIM

The ornamental design for a water bottle with lid, as shown and described.

DESCRIPTION

FIG. 1 is a front, right and top perspective view of a water bottle with lid, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the water bottle with lid shown with an alternate environment; and,

FIG. 10 is another front, right and top perspective view of the water bottle with lid shown with an alternate environment.

The even dash broken lines depict portions of the water bottle with lid and environment that form no part of the
